DISCHARGE TUBE

Original application filed December 19, 1927, Serial No. 241,035, and in Germany December 10, 1926.
Divided and this application filed February 9, 1928. Serial No. 253,040.

The present invention relates to discharge tubes, such as colored glow tubes for advertising purposes, ultra violet ray tubes, and the like, and more particularly to means facilitating the starting of such tubes into operation without using potentials higher than those available for the general operation of such tubes.

In our copending applications Serial Numbers 241,034 and 241,035, filed December 19, 1927, we describe and claim the construction and arrangement of such tubes permitting operation of them directly from low potential commercial lighting and power systems, such as 110 and 220 volt systems, including in particular arrangements permitting satisfactory operation with alternating current at such low potentials. We provided electron emitting electrodes alternately acting as cathodes and anodes to reduce by reason of electron emission the so-called cathode fall or drop of potential, describing both separately heated electron emitting cathodes and cathodes deriving electron emitting heating from the ionic bombardment taking place after the discharge has been started. In the case of the latter type of cathode we provided auxiliary electrodes in close proximity as starting electrodes, this because the tube must be started cold and without any way of bringing on electron emission until ionic bombardment is had.

This application is a division of our copending application Serial Number 241,035, filed December 19, 1927, and relates particularly to the elimination of the difficulty had in starting a gas filled tube having a plurality of incandescent electrodes, a reason different from that which has long prompted the use of starting devices with initially cold cathodes, so that without special provision a starting potential considerably higher than that required for continued operation after the discharge has been created may be required for the separately heated type of

cathode. This condition arises from the initially hot cathode creating about itself a field or cloud of electrons which, though later are most desirable, act to prevent the commencement of ionization by being sufficient in number to neutralize ions as fast as created. Once the discharge is developed the ions predominate, and the electron field is thereafter incapable of subduing the ionization.

We have found that a positively charged body or auxiliary electrode in the neighborhood of the electron emitting cathode so dispenses the electron cloud while the main discharge potential is producing a sufficiently intensive ionization to overcome the entire electron field if later released from the influence of the auxiliary charged body that starting of the main discharge can be readily had with any excess potential.

The one figure of the drawings illustrates the manner in which the desired result is accomplished. The tube VT includes a gas filling of desired character and pressure to produce the glow discharge or other result desired of the tube. It includes electrodes F₁ and F₂, mounted in suitable stems S₁ and S₂ in the two ends, having suitable lead-in wires all common in practice. The electrodes F₁ and F₂ are coated with suitable electron emitting compounds capable of withstanding considerable ionic bombardment, and must be so capable because they alternately act as cathodes and anodes when alternating current is used. These electrodes are heated for electron emission by current passing through them derived from secondary windings S₁ and S₂ of suitable potentials of the alternating current transformer illustrated.

The two electrodes have impressed across them the full line potential, as can be seen from tracing the leads L₁, L₂ connected at opposite ends of primary P to the center tap connections in secondaries S₁, S₂ connected to the electrodes.

The auxiliary electrodes A_1 and A_2 are placed close to electrodes F_1 and F_2 respectively, and have in series with their external leads resistances R_1 and R_2 . When circuit breakers B_1 and B_2 are down, as they are before the main discharge commences, it will be seen that the line potential is across each main electrode and its corresponding auxiliary electrode, and if any discharge takes place between these electrodes it is limited by the series resistance to any degree desired by choice of value of this resistance. As soon as the main discharge takes place large current flows through the pick-up coils of circuit breakers B_1 and B_2 to open the auxiliary circuits, thus preventing waste of current after the auxiliary system has served its purpose; though the circuit breakers may be omitted and resistances R_1 and R_2 made so large as to keep the auxiliary current sufficiently low to keep the waste current reasonably low.

Having described our invention we claim:

1. In a glow lamp system including an envelope having a gas therein, a plurality of incandescent electrodes spaced apart therein and auxiliary electrodes in close proximity to each of said incandescent electrodes, the combination of a transformer having a primary and a plurality of secondaries corresponding in number to said incandescent electrodes, connections between each secondary and its corresponding electrode, connections between each secondary and each terminal of said primary, and a connection between each terminal of said primary and the auxiliary electrode adjacent the incandescent electrode electrically connected to the other terminal of said primary whereby the electron field around the incandescent electrode acting as an anode is dispersed and ionization of the gas surrounding said electrode is developed.

2. In a glow lamp system including an envelope having a gas therein, a plurality of incandescent electrodes spaced apart therein and auxiliary electrodes in close proximity to each of said incandescent electrodes, the combination of a transformer having a primary and a plurality of secondaries corresponding in number to said incandescent electrodes, connections between each secondary and its corresponding electrode, connections between each secondary and each terminal of said primary, each connection containing an impedance of predetermined value, and a connection between each terminal of said primary and the auxiliary electrode adjacent the incandescent electrode electrically connected to the other terminal of said primary whereby the electron field around the incandescent electrode acting as an anode is dispersed and ionization of the gas surrounding said electrode is developed.

3. In a glow lamp system including an

envelope having a gas therein, a plurality of incandescent electrodes spaced apart therein and auxiliary electrodes in close proximity to each of said incandescent electrodes, the combination of a transformer having a primary and a plurality of secondaries corresponding in number to said incandescent electrodes, connections between each secondary and its corresponding electrode, connections between each secondary and each terminal of said primary, circuit breakers, the coil of each of which is contained in one of said last named connections, and a connection between each terminal of said primary and the auxiliary electrode adjacent the incandescent electrode electrically connected to the other terminal of said primary, said connections containing the contacts of said circuit breakers whereby the electron field around the incandescent electrode acting as an anode is dispersed and ionization of the gas surrounding said electrode is developed.

4. In a glow lamp system, the combination of an envelope having a gas therein, a plurality of incandescent electrodes spaced apart therein, a corresponding number of auxiliary electrodes each in close proximity to said incandescent electrodes and means for maintaining the auxiliary electrode of one incandescent electrode at a definite potential relative to the potential of another of said incandescent electrodes, means between said auxiliary electrode and said main electrode for maintaining the value of current flow therebetween at a value less than the value of said current flow between said main electrodes, said last mentioned means consisting of a resistance the effective value of which is higher than the resistance of said tube between said main electrodes when in operating condition, and means for disconnecting said auxiliary electrodes when current flows between said incandescent electrodes, said means consisting of a plurality of circuit breakers, the coils of which are contained in the circuits between the main electrodes and the contacts of which are included in the circuits of said auxiliary electrodes.

CERTIFICATE OF CORRECTION.

Patent No. 1,843,645.

Granted February 2, 1932, to

FRIEDRICH MEYER ET AL.

It is hereby certified that error appears in the printed specification of the above numbered patent requiring correction as follows: Page 1, line 38, strike out the comma and words ", a reason" and insert instead a period and the words This difficulty is; lines 58 and 59, for "dispenses" read disperses, and line 65, for "with" read without; and that the said Letters Patent should be read with these corrections therein that the same may conform to the record of the case in the Patent Office.

Signed and sealed this 22nd day of March, A. D. 1932.

(Seal)

**M. J. Moore,
Acting Commissioner of Patents.**
